(57) **CLAIM**

The ornamental design for a kayak circle bucket, as shown and described.

DESCRIPTION

FIG. 1 is a top perspective view of a first embodiment of a kayak with the circle bucket inside.

FIG. 2 is a bottom perspective view of the kayak of FIG. 1. FIG. 3 is a top plan view of the circle bucket inside the kayak of FIG. 1.

FIG. 4 is an enlarged detail view, taken from FIG. 3, of the kayak circle bucket of FIG. 1.

FIG. 5 is a bottom plan view of the kayak of FIG. 1.

FIG. 6 is a left side view of the kayak of FIG. 1.

FIG. 7 is a right side view of the kayak of FIG. 1.

FIG. 8 is a front view of the kayak of FIG. 1.

FIG. 9 is a back view of the kayak of FIG. 1.

FIG. 10 is a partial enlarged front perspective view of the circle bucket of FIG. 1.

FIG. 11 is a partial enlarged rear perspective view of the circle bucket of FIG. 1.

FIG. 12 is a top perspective view of a second embodiment of a kayak with the circle bucket inside.

FIG. 13 is a bottom perspective view of the kayak of FIG. 12.

FIG. 14 is a top plan view of the kayak with the circle bucket of FIG. 12.

FIG. 15 is an enlarged detail view, taken from FIG. 3, of the circle bucket of FIG. 12.

FIG. 16 is a bottom plan view of the kayak of FIG. 12.

FIG. 17 is a left side view of the kayak of FIG. 12.

FIG. 18 is a right side view of the kayak of FIG. 12.

FIG. 19 is a front view of the kayak of FIG. 12.

FIG. 20 is a back view of the kayak of FIG. 12.

FIG. 21 is a partial enlarged front perspective view of the circle bucket taken from FIG. 12.

FIG. 22 is a partial enlarged rear perspective view of the circle bucket taken from FIG. 12.

FIG. 23 is a top perspective view of a third embodiment of a kayak with the circle bucket inside.

FIG. 24 is a bottom perspective view of the kayak of FIG. 23.

FIG. 25 is a top plan view of the kayak with the circle bucket of FIG. 23.

FIG. 26 is an enlarged detail view, taken from FIG. 25, of the circle bucket of FIG. 23.

FIG. 27 is a bottom plan view of the kayak of FIG. 23.

FIG. 28 is a left side view of the kayak of FIG. 23.

FIG. 29 is a right side view of the kayak of FIG. 23.

FIG. 30 is a front view of the kayak of FIG. 23.

FIG. 31 is a back view of the kayak of FIG. 23.

(Continued)

FIG. 32 is a partial enlarged front perspective view of the circle bucket taken from FIG. 23; and,

FIG. 33 is a partial enlarged rear perspective view of the circle bucket taken from FIG. 23.

The dash-dash broken lines within the claimed circle-bucket, illustrate portions of the article and form no part of the claimed design.

The dash-dash broken lines showing a kayak, depict environmental structure and forms no part of the claimed design. The dash-dot-dash broken lines in FIGS. 3, 4, 14, 15, 25 and 26, and the dash-dash lines surrounding FIGS. 10, 11, 21, 22, 32, and 33 depicts the boundaries of the enlargements and forms no part of the claimed design.

1 Claim, 24 Drawing Sheets
